CLAIM

The ornamental design for a file with a pocket, as shown and described.

DESCRIPTION

FIG. 1 is a perspective view of a file with a pocket showing our new design;

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof; and,

FIG. 8 is a perspective view thereof with the pocket in a closed position.

The portions shown in phantom lines are not part of the claimed invention, but are considered necessary to show environment.
